UNITED STATES PATENT OFFICE.

HERBERT W. HOOVER, OF NEW BERLIN, OHIO, ASSIGNEE, BY MESNE ASSIGNMENTS,
TO THE HOOVER COMPANY, OF NORTH CANTON, OHIO, A CORPORATION OF OHIO.

SUCTION CLEANER.

Application filed September 10, 1917. Serial No. 190,431.

To all whom it may concern:

Be it known that I, HERBERT W. HOOVER, a citizen of the United States, residing at New Berlin, in the county of Stark and State of Ohio, have invented a certain new and useful Improvement in Suction Cleaners, of which the following is a specification.

My invention relates to suction cleaners and has amongst other things for its object to provide speed reducing means which shall contain two pulleys lying in the same plane and in a horizontal plane whereby the height of the machine is not increased and it further provides means whereby the brush driving parts are elastically held in operative relation and particularly it accomplished this latter result by the elasticity of the driving belt itself. Other objects will appear from time to time as the description proceeds.

I have illustrated my invention in connection with a suction cleaner of a familiar type, but it will be understood that it is applicable to any kind of cleaner where a brush is used and motive power applied to drive the brush. The invention is illustrated in the accompanying drawings wherein:—

Figure 1 is a bottom view, with the hand hole cover removed;

Figure 2 is a section on the line 2—2 looking in the direction indicated by the arrows;

Figure 3 is a bottom view of a modification;

Like parts are indicated by the same letter in all the figures.

A is the casing of any desired size, shape or proportion of parts. B is the mouth, nozzle or inlet.

C is the brush of any desired structure and supported in any desired manner in the casing near the mouth.

I do not show the details of its support. It is provided with a driving pulley D, in this case placed near the middle of the brush and E is the belt by which the brush is driven.

F is the motor casing, suitably mounted on the cleaner casing, and containing the motor G.

The motor shaft H projects into the fan chamber N where it carries and drives the fan J, and on the lower end of this fan shaft is a driving hub or pulley

K which projects through the hole L between the dust chamber M and the fan chamber N. The hub is secured to the shaft in any desired manner, and the details are not shown. At one side of the opening L there is a boss or enlargement O in the partition which separates the dust and fan chambers, and in the dust chamber is a screw having the slotted head P, with a body P¹, a shoulder P², to engage the lower surface of the partition or boss and the screw-threaded portion P³ to be received into the screw-threaded aperture in the boss O. P⁴ is an anti-friction washer between the head of this screw and the hub portion P⁵ of the arm Q.

By this means the arm Q is held pivotally in the position indicated. At its other end this arm is provided with a hub R, and is screw-threaded to receive the screw-threaded end R¹ of a screw which is provided with the shoulder R², the body R³, the slotted head R⁴, and the friction washer R⁵. On the body of this screw is mounted the belt pulley S, and rotatable therewith the friction drive wheel S¹. T, T are the forward supporting wheels arranged in any desired manner, details not here shown, and U, U are the rear driving wheels in like manner here illustrated without adjustable details such as are commonly used.

V is the outlet passageway.

Referring to the modification shown, the hub K engages a wheel W which is pivoted on an arm W¹, in turn pivoted at W² to the casing. This arm has a stop W³ which engages the end of a set screw W⁴. W⁵ is a spring secured to the arm and to the casing and placed so as to tend to swing the arm on its pivot and force the wheel W against the hub K. The driving belt is in this case driven from a pulley W⁶ concentric with the wheel W.

It will be understood that I have shown somewhat diagrammatically the general structure and also modifications of my device and I do not wish to be limited to the particular size, shape, proportion and arrangement of the parts, as these or some of them can be altered without departing from the spirit of my invention.

It will be noted that the two pulleys are in one and the same plane and that they are arranged in a horizontal plane and the belt pulley is also arranged in an adjacent hori-

zontal plane. If the shaft is tilted, then, of course, these pulleys would be tilted and thus the plane could depart from the horizontal but in any other case it would be perpendicular to the motor shaft.

By operating the screw W^4 the pulleys may be separated by swinging arm W^1 to one side and thus the driving connection between the brush and the motor may be broken. This might be desirable from time to time and might particularly be desirable when the converter is to be used. By converter I mean the connection which is used when the inlet mouth adjacent the brush is not used and some other device is provided for use usually on some other than the floor surface or floor covering. I have not shown any such mechanism in connection with the device illustrated in Figures 1 and 2 but it will be understood that in like manner means could be employed to separate the speed reduction pulleys there if desired. That means could be similar to what is illustrated in Fig. 3. This might also be desirable under certain circumstances where and when the brush was no longer needed. In this case by separating and locking in separated position the speed reduction and power transmission pulleys the brush would be stopped and the motor will tend to speed up the fan thus taking a larger volume of air through the apparatus.

The use and operation of my invention are as follows:—

35 When suction cleaners are provided with driving brushes and means and motors for driving such brushes, a good deal of difficulty is encountered from various causes. The fan must be driven at a high rate of speed. The brush should be driven from the same motor at a much lower rate of speed. The bearings give a great deal of trouble. On account of these and other difficulties and necessities I have invented the means here illustrated. Where a friction drive is employed in such a suction cleaner the separable parts of the driving mechanism will permit dust and dirt and foreign objects to pass therethrough, the parts simply separating enough to permit such passage, and being yieldingly held they are immediately restored to working position. It is of course highly desirable to minimize the mechanism in such an appliance, hence I prefer to use the elastic belt which is necessary in a belt driven brush to yieldingly hold the driving parts together. If, as is here illustrated, a reduction drive is produced, and the parts are properly proportioned, one result which is desirable flows from my invention in addition to those results which have been previously suggested. If the belt breaks or escapes from its pulley, all the transmitting mechanism is stopped except of course the motor shaft.

This immediately takes the load of the brush and driving mechanism off the motor, whereupon the latter speeds up for the purpose first, of taking through a greater quantity of air which by its cleaning effect in part compensates for the lack of the brush, and second, for giving a signal to the operator by the sound of the motor to notify the operator that the brush has stopped. Obviously the relative size of the rotating driving parts could be as desired. The friction drive wheel associated with the pulley can be supported in any desired manner. It is preferably supported so that it will be on the opposite side of the driving shaft from the brush, and it is also preferably supported on a swinging arm which could be enclosed within the casing. Of course various other devices could be utilized to support this friction pulley and it could be easily arranged so that the belt could run open instead of twisted.

In the structure of Fig. 3, as previously explained, the driven wheel is elastically held by means other than the belt against the driving wheel or hub.

I call attention further to the fact that the bearings in the friction wheel and driving pulley are preferably oilless wood bearings the object being to avoid the use of oil if possible or if found always desirable in a structure where the bearings are working in or adjacent to an atmosphere heavily charged with dust.

I claim:

1. In a suction cleaner the combination of a casing, a brush, a driving means including a shaft, an elastic driving belt for the brush, means for connecting the driving means with the belt comprising one friction wheel on the shaft of the driving means, and one friction wheel associated with a pulley and movably mounted whereby the elasticity of the belt alone yieldingly holds the friction wheels operatively together, the driving shaft friction wheel being mounted between the other friction wheel and the brush.

2. In a suction cleaner the combination of a casing, a brush rotating on a horizontal axis, a driving means including a vertical shaft an elastic driving belt for the brush, means for connecting the driving means with the belt comprising friction driving devices, one on the shaft of the driving means, the other movable toward the shaft but on the side opposite the brush, the two friction driving devices being in the same horizontal plane, and a belt pulley associated with such movable friction devices whereby the elasticity of the belt alone yieldingly holds the driving devices operatively together.

3. In a suction cleaner the combination of a casing, a brush, a driving means including a shaft, an elastic driving belt for the brush,

- a driving wheel on the shaft of the driving means, a driving wheel and belt pulley mounted on a pivoted arm so as to be movable toward the shaft whereby the elasticity 5 of the belt alone yieldingly holds the driving wheels operatively together, the friction wheel on the driving shaft located between the brush and the movable friction wheel.
4. In a suction-sweeper, the combination, 10 with a fan-shaft and a brush, of a drive-member on the fan-shaft; a friction-wheel movably supported so that it may be moved towards and from the drive-member; and belt-and-pulley connections between the friction-wheel and the brush, the belt being of 15 elastic material and extending in a direction such that its tension tends to draw the friction wheel into engagement with the drive-member.
- 20 5. In a suction sweeper, the combination with a fan-shaft and a brush, of a drive-member on the fan shaft, a friction wheel movably supported so that it may be moved towards and from the drive member, and 25 belt-and-pulley connections between the fric-
- tion-wheel and a brush, the belt being of elastic material and extending in a direction such that its tension tends to draw the friction-wheel into engagement with the drive-member and means for drawing the friction wheel out of contact with the drive member, against the tension of the belt. 30
6. In a suction cleaner, the combination of a casing, a rotating brush therein provided with a pulley, a driving-shaft, a friction-wheel on said driving-shaft, a bodily-movable friction wheel and pulley, an elastic-belt connecting said pulleys and tending to keep the said wheels in contact, and means for moving the bodily-movable wheel out of contact with the other wheel against the tension of the belt. 35

In testimony whereof, I affix my signature in the presence of two witnesses this 28th day of August 1917.

HERBERT W. HOOVER.
